UNITED STATES PATENT OFFICE.

DANIEL W. SCHNEBBE, OF RICHMOND HILL, NEW YORK.

FOUNTAIN-PEN.

No. 889,973.

Specification of Letters Patent.

Patented June 9, 1908.

Application filed January 16, 1908. Serial No. 411,068.

To all whom it may concern:

Be it known that I, DANIEL W. SCHNEBBE, a citizen of the United States, residing at Richmond Hill, New York, have invented 5 certain new and useful Improvements in Fountain-Pens, of which the following is a clear, full, and exact description.

The object of this invention is to provide within one holder of a fountain pen at least 10 two individual pen points, together with reservoirs adapted to contain if desired more than one kind of ink.

In carrying out this invention, I make use of a simple tubular barrel having slotted 15 openings in the side thereof, and within the barrel longitudinally sliding therein, I locate a plurality of ink reservoirs; preferably each in the shape of half a cylinder in cross section. Within the single tubular case or 20 holder I provide a suitable gearing connecting the individual reservoirs so that upon the projection of one reservoir the other will necessarily be withdrawn from the open end of the tubular receptacle.

25 I further provide suitable valve means to prevent ink from flowing in that pen which is at the time retracted in position. Such suitable valve means is preferably a ball adapted to close the orifice through the pen stock; 30 and I further provide tracks having sharp apices on which the ball may travel without sticking thereto through gummy deposits. I further provide a cover for the holder, which 35 will engage projecting studs on the independent reservoirs, and by the mere insertion of the cap in place both pens will be likewise withdrawn an equal distance into the receptacle.

The scope of my invention will be set forth 40 in the claims.

In the accompanying drawings Figure 1 is a front elevation of my improved pen holder with the cap in section. Fig. 2 is a transverse section of the holder proper with one of 45 the independent reservoirs shown partly in section. Fig. 3 is a section on line 3—3 Fig. 2 with the links removed. Fig. 4 is a section on line 4—4 Fig. 5. Fig. 5 is a detail of the valve cage provided with the tracks and is 50 shown partly in section, on line 5—5, Fig. 4. Fig. 6 is a section of the valve cage on line 6—6 Fig. 4. Fig. 7 is a section showing the gearing taken on line X X Fig. 1.

In carrying out my invention I provide a 55 tubular holder 1, having slotted openings on opposite sides 2—3, and having a threaded

lower end 4, which is secured to the main body of the holder as at 5 by screw threads. Each longitudinally slidable reservoir 5 and 6 is provided with an eye 7 at its upper end, to 60 which is connected a link 8 in turn pivoted to a link 9, which is secured to a pivot point 10 on a wheel 11, journaled in bearings 12 in the upper end of the tubular case or holder 1. Knee plates 13 are secured to the links 9 so 65 that the links 8 and 9 may be maintained rigid upon the projection of their reservoir member, and thus prevent the accidental retraction of the same. Each reservoir carries a removable pen stock 14, which may be 70 fitted thereto in the ordinary way.

I prefer to form around the lower edge of the pen stock grooves or notches 15 for engagement with one's fingers to aid in removing the pen stock when it is necessary. 75 The pen stock carries the ordinary pen 16, and feeder 17, which is fed with ink through an opening 18 through the pen stock. The opening 18 is at the upper end surrounded by a collar like projection 19, so that a ball 80 20 carried within the valve cage will never touch the surface of the pen stock except when taking a position over the orifice 18. The cage which surrounds the ball is in reality a succession of tracks, on which the 85 ball may run bearing against their sharp edged apices; thus doing away with any tendency which the ball may have to stick to the surface due to ink coatings thereon.

The cage is made open at the top, though 90 the opening is of a less width than the ball 20, and it is formed with two downwardly projecting tracks 21, which are occasioned by the turned over edges of the side plates 22 of the cage. The ends of the cage to the 95 right may be similarly turned-in to form tracks 23 while the right hand end of the cage I prefer to provide with a single track 24. At the bottom of the cage and to the right I provide a small track 25. It will be 100 seen that the ball, while it may touch the sides 22 of the cage at some times, can never really rest its weight when in motion on anything but the sharp edged tracks; consequently it is kept from sticking within 105 the cage.

While I have shown certain of the tracks as single rails and others as double rails, it will be obvious that double rails throughout or single rails throughout might readily be 110 used according to the desires of the maker. The cage is fastened to the top of the pen

stock, and in the modification shown in these drawings the cage may be made of one single stamping, although it will readily be understood that I do not limit myself to so constructing it.

Through the slots 2 and 3 of the casing 1, I project pins 26—27. One of these pins I preferably make black and the other one red, and I fasten them in place in their respective reservoirs by threading their ends, so that they may be removed if desired to permit the filling of the pen through the orifice left by their removal, the air within the reservoirs escaping through the pen stock. 15 When it is desired to clean the pen, the extension 4 is removed and the pens placed in the position of Fig. 2, when the pen stock 14 may be taken from its reservoir, and the reservoir cleaned.

20 The cap 28 is notched preferably at 29 on opposite sides of the same, so that when slid into place the notches 29 will engage with the pins 26—27 respectively, and retract the extended pen so that it can not 25 contact with the material of the cap and become damaged.

From the position of the valve 20 in Figs. 4 and 5 it will be seen that when a pen is held so as to write with the projected pen 30 point the valve will have rolled on its tracks to the right in Fig. 5, thus engaging the orifice, but when the pen is being used in the position shown in Fig. 2 the valve 20 of the left hand pen stock will roll to the left and 35 cover the orifice, thus preventing feed from any pen, but the one which is being used by the writer at that time. In operation one would remove the cap and push forward that pen which controls the ink desired, 40 whereupon that reservoir would pull its links down, rotate wheel 11, retract the links of the other reservoir, and lift the other reservoir into its retracted position.

I claim as my invention:

45 1. The herein described fountain pen, comprising two independent reservoirs adapted to be freely reciprocated, a single casing, and means to reciprocate the reservoirs within the casing, the pen points of each independent 50 reservoir pointing in the same direction.

2. The herein described fountain pen, comprising two independent reservoirs, a single casing for the reservoirs, the pen points of the reservoirs pointing in the same direction, a 55 removable open ended sleeve at one end of the casing, and a pen and pen stock for each reservoir.

3. The herein described fountain pen, comprising a casing two independent reservoirs, 60 means for reciprocating the same, pen points for the reservoirs pointing in the same direction, said casing being provided with slots, projecting pins passing through said slots and secured, one in each reservoir, each pin 65 being secured in its reservoir so that it will

be readily removed, each reservoir being provided with an aperture normally closed by its pin, and adapted to be opened upon the removal of the pin, for filling.

4. The herein described fountain pen comprising two reservoirs, a single casing for the reservoirs, the pen points of the reservoirs pointing in the same direction, a rocking member, gearing connecting the reservoirs comprising double links, each pair of double 75 links connecting it to the rocking member at one end and to the reservoir at the other end.

5. The herein described fountain pen, comprising two reservoirs, a single casing for the reservoirs, the pen points of the reservoirs 80 pointing in the same direction, a rocking member, gearing connecting the reservoirs comprising double links, each pair of double links connected to the rocking member at one end, and to a reservoir at the other end, 85 and a knee plate for the links.

6. A fountain pen comprising a casing, two independent longitudinally movable reservoirs, links therefor, a rocking member at one end of said casing, connected by said 90 links with the said two independent reservoirs, removable pen stocks for the reservoirs, said casing having slots therein, pins for the reservoirs projecting through said 95 slots and a removable sleeve at the open end of the casing.

7. A fountain pen comprising a casing, two independent longitudinally movable reservoirs, links therefor, a rocking member at one end of said casing, connected by said 100 links with the said two independent reservoirs, removable pen stocks for the reservoirs, said casing having slots therein, pins for the reservoirs projecting through said 105 slots and a removable sleeve at the open end of the casing, and a gravity valve adjacent to each pen stock adapted to prevent flow of ink from that pen not in use.

8. A fountain pen having two reservoirs adapted to be reversely reciprocated, a common casing therefor, and a valve means in each reservoir, a pen stock having a feed outlet, said valve means being adapted to close the outlet of that pen which is retracted when the device is in use.

9. The fountain pen having two reservoirs adapted to be reversely reciprocated, a common casing therefor, and a valve means in each reservoir, a pen stock having a feed outlet, said valve means being adapted to close the outlet of that pen which is retracted when the device is in use, a cage for said valve and tracks therein adapted to hold the valve free from the sides, said valve comprising a spherical body.

10. A fountain pen comprising a casing, two longitudinally movable reservoirs having in combined cross section the configuration of the interior of the casing, operating means within said casing connecting the reservoirs 120

and adapted to hold one pen retracted when the other is projected, a pen stock having a feed orifice, a pen for each reservoir, and a gravity valve adapted to automatically locate itself over the feed orifice of that pen stock which is retracted when the pen casing is in use for writing.

11. A fountain pen comprising a casing having slots, two longitudinally movable reservoirs having in combined cross section the configuration of the interior of the casing, operating means within said casing connect-

ing the reservoirs, and adapted to project one pen upon the retraction of the other, a pen stock and pen for such reservoir, a pin ¹⁵ secure to and passing through the wall of a reservoir, and projecting through one of the slots in the casing, said pin being removable.

Signed at New York city this 15th day of January 1908.

DANIEL W. SCHNEBBE.
